US00D899709S

(12) **United States Design Patent** (10) Patent No.: **US D899,709 S**
MacNeil et al. (45) Date of Patent: ** Oct. 20, 2020

(54) **PET WATER STATION**(71) Applicant: **MACNEIL IP LLC**, Bolingbrook, IL (US)(72) Inventors: **David F. MacNeil**, Fort Lauderdale, FL (US); **Frederick W. Masanek, Jr.**, Barrington, IL (US)(73) Assignee: **MACNEIL IP LLC**, Bolingbrook, IL (US)(**) Term: **15 Years**(21) Appl. No.: **29/731,049**(22) Filed: **Apr. 10, 2020****Related U.S. Application Data**

(60) Division of application No. 29/621,052, filed on Oct. 4, 2017, now Pat. No. Des. 887,650, which is a continuation-in-part of application No. 29/602,916, filed on May 4, 2017, now Pat. No. Des. 873,503, which is a continuation-in-part of application No. 29/560,208, filed on Apr. 4, 2016, now Pat. No. Des. 802,853.

CLAIM

We claim the ornamental design for a pet water station, as shown and described.

DESCRIPTION

FIG. 1 is a top perspective of a pet water station in accordance with our design;

FIG. 2 is a top perspective exploded view thereof;

FIG. 3 is a bottom perspective exploded view thereof;

FIG. 4 is a top view thereof;

FIG. 5 is a front view thereof;

FIG. 6 is a rear view thereof;

FIG. 7 is a left side view thereof, a right side view thereof being a mirror image of the left side view;

FIG. 8 is a top perspective view of a combined mat and stand used in our design;

FIG. 9 is a top view of the combined mat and stand shown in FIG. 8;

FIG. 10 is a front view of the combined mat and stand shown in FIG. 8;

FIG. 11 is a rear view of the combined mat and stand shown in FIG. 8;

FIG. 12 is a left side view of the combined mat and stand shown in FIG. 8, a right side view thereof being a mirror image of the left side view;

FIG. 13 is a sectional view taken along Line 13-13 of FIG. 9; and,

FIG. 14 is a sectional view taken along Line 14-14 of FIG. 9.

The bottom of the assembled pet water station shown in FIGS. 1-7, which is the same as the bottom of the combined mat and stand shown in FIGS. 8-14, is unadorned and forms no portion of the claimed design. The broken line showing

of the environment is for illustrative purposes only and forms no part of the claimed design.
